UNITED STATES PATENT OFFICE

HENRY R. JACKSON, OF NEWARK, NEW JERSEY

SHAMPOO CHIN REST

Application filed May 21, 1931. Serial No. 538,894.

This invention relates particularly to a rest or support for the chin of a person during a shampooing operation, one object of the invention being to provide a novel and improved rest which can be separably attached to a lavatory basin to support the chin of a person while his hair is being shampooed.

Another object is to provide a chin rest of this character which shall be comfortable and sanitary.

A further object is to provide a novel and improved construction and combination of a soft pad or cushion for the chin, and a lavatory basin, whereby a sanitary cover, such as tissue paper, may be removably applied to the pad or cushion and easily and quickly secured in position between the pad and the basin, so that the pad can be repeatedly used for a number of patrons and a separate sanitary cover can be used for each patron.

Other objects are to provide a novel and improved construction and combination of a cushion or pad and a lavatory basin, wherein the basin or pad has a rib or groove to cooperate with a corresponding groove or rib on the other part; to provide in a shampoo chin rest novel and improved means for separably connecting a cushion or pad to a lavatory basin whereby accidental displacement of the pad during a shampooing operation is prevented; and to obtain other advantages and results as will be brought out in the following description.

Referring to the accompanying drawing, in which corresponding and like parts are designated throughout the several views by the same reference characters,

Figure 1 is a top plan view of a shampoo chin rest embodying my invention;

Figure 2 is a transverse vertical sectional view, on the line 2—2 of Figure 1;

Figure 3 is a transverse sectional view, on the line 3—3 of Figure 1, and

Figure 4 is a bottom plan view of the cushion or pad.

Specifically describing the illustrated embodiment of the invention, the reference character A designates a lavatory basin in gen-

eral of the usual construction, including a rim 1 and the usual bowl 2.

On the top of the rim 1 of the basin, and preferably at the front side of the basin, is provided a groove 3 the sides of which are 55 preferably undercut at 4 and converge inwardly toward each other from the edge of the rim to the bowl 2, as shown in Figures 3 and 1, respectively.

A cushion or pad B is removably mounted in said groove 3, said cushion or pad being shown in the present instance as consisting of a sponge rubber body 5 having a base or rib 6 of relatively hard material of a shape and size corresponding to the groove 3. This 65 base 6 may be molded integrally with the body 5, or may constitute a separate piece secured to the body as may be desired. The pad 5 is preferably of such a size that its sides extend beyond the sides of the base 6, 70 as clearly shown in Figure 4 of the drawing.

In use of the chin rest, the base 6 of the pad B is slipped into the groove 3 from the front side of the rim A with a wedge action, 75 so that the undercut sides 4 of the groove hold the pad against vertical displacement, while the convergence of said sides toward the bowl limit movement of the pad in that direction. The relative sizes of the parts are 80 preferably such that when the pad is so mounted, the bottom side of the pad projecting outwardly beyond the side edges of the base 6 is in close relation to the top of the rim A.

After the pad has been so arranged, a strip 85 of tissue paper or other suitable flexible material 7 may be placed over the top of the pad with its ends tucked between the pad and the rim A of the basin, as clearly shown in Figure 3 of the drawing. The pad being resilient, and the underside thereof being arranged in close relation to the top of the rim A, the ends of the sheet 7 are thus removably and frictionally clamped so as to hold the strip against displacement. To remove the strip it is merely necessary to pull the ends 90 thereof outwardly from beneath the pad.

With this construction, it will be observed that a comfortable, secure and sanitary rest 95 for the chin of a person during a shampooing

operation is provided, having a minimum number of parts which are simple in construction and operation. There are no metal or other parts to cause injury; the pressure of the chin on the pad during the shampooing operation tends to force the base 6 of the pad into tighter engagement with the walls of the groove 3 so that possibility of displacement of the pad by pressure upon the head of the person, is reduced. The pad can be easily and quickly applied to and removed from the basin, and a separate sanitary covering 7 for the pad may be easily and quickly provided for each patron. The groove 3 easily can be kept clean, and does not materially alter the basin.

While I have shown and described the invention as embodied in certain details of construction, it should be understood that this is primarily for illustrating the principles of the invention, and that many modifications and changes may be made in the details of construction without departing from the spirit or scope of the invention.

25 Having thus described the invention, what I claim is:

1. The combination of a lavatory basin having a rim, a resilient chin pad, means for securing said chin pad on said rim with a portion of said pad in close and resiliently movable relation to said rim, and a cover for said pad having portions clamped between said pad and said rim to secure said cover in position on said pad.

2. The combination of a lavatory basin having a rim, a chin pad, one of said parts, chin pad and rim, having an undercut groove and the other part having a rib to fit said groove for securing said pad on said rim, said pad having resilient parts projecting beyond said rib and groove and overlying said rim in close relation, and a cover for said pad having portions clamped between said projecting portions of the pad and said rim.

3. The combination of a lavatory basin having a rim, a chin pad, said rim and said chin pad having cooperating parts for removably mounting said pad on said rim, said pad having parts in resiliently movable close relation to said rim, and a cover for said pad having portions clamped between said resiliently movable parts of said pad and said rim to removably secure said cover in position on said pad.

4. The combination of a resilient chin pad and a support therefor, said chin pad being secured on said support with a portion of said pad in close and resiliently movable relation to said support, and a cover for said pad having portions clamped between said pad and said support to secure said cover in position on said pad.

HENRY R. JACKSON.
